CLAIM

The ornamental design for a toy as shown and described.

DESCRIPTION

FIG. 1 is a perspective view of a toy showing my new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines immediately adjacent to the shaded areas depict the bounds of the claimed design, while all other broken lines show portions of the toy that form no part of the claimed design. The broken lines form no part of the claimed design. The shade lines in the Figures show contour and do not claim surface ornamentation or treatment.
